UNITED STATES PATENT OFFICE.

EDWARD FURROW, OF SPRINGFIELD, ILLINOIS.

RAILWAY STRUCTURE.

1,346,312.

Specification of Letters Patent. Patented July 13, 1920.
Application filed July 14, 1919. Serial No. 310,583.

To all whom it may concern:

Be it known that I, EDWARD FURROW, a citizen of the United States, resident in the city of Springfield, county of Sangamon, 5 and State of Illinois, have invented a new and useful Railway Structure, of which the following is a specification.

The invention relates to the track structure of railways. The purposes of the invention are; to provide a permanent road bed; to provide simple and effective means for draining the road bed; to provide chairs of improved construction adapted to support the rails, true to gage, and prevent them from spreading; to provide locking devices of improved construction to secure the rails on the chairs and adapted to be released when it is desired to replace a rail or rails; 20 to provide cushions under the chairs to deaden sound and absorb shocks; and to provide improved structural details, as will hereinafter appear.

The invention is illustrated in the annexed drawings, to which reference is hereby made, 25 and will now be described and the novel features thereof will be recited in the claims.

Figure 1 is a top plan of part of a railway embodying my invention; Fig. 2 is a vertical transverse section on the line X. X. of Fig. 30 1; Fig. 3 is a vertical longitudinal section on the line Y. Y. of Fig. 1; Fig. 4 is an enlarged view showing partly in transverse section, one rail, one chair, one cushion and one bed-plate; and Fig. 5 is a vertical section parallel to the rail through one locking block, one chair, one cushion and one bed 35 plate, taken on the line Z. Z. of Fig. 4.

The same reference numerals designate the same parts in all the views.

The preferred embodiment of my invention, illustrated in the drawings, comprises:

A concrete road bed 1 having a longitudinal draining channel 2; drain pipes 3 to carry water away from the drainage channel; filter beds 4 of porous material, such as cinders, to strain the water going to the drain pipes to prevent clogging of the pipes; box-shape bed-plates 5 embedded in the concrete road-bed; cushions 6 of asphalt, or other yielding material, contained in the boxes of the respective bed-plates; chairs 7 supported on the cushions in the bed plates and capable of slight vertical guided movement relative to the bed-plates; tie-rods 8 embedded in the concrete road bed and connecting the chairs on the opposite sides of

the road bed to keep the chairs true to gage; rails 9 supported on the chairs; locking blocks 10 supported on the respective chairs and pivotally connected therewith; lengthening members 12 attachable to the respective locking blocks at the free ends of the blocks, 60 to adapt the locking blocks to engage and hold rails having webs of different thickness; and keys 13 for holding the locking 65 blocks in locked position.

The rails 9 may be of any usual or approved construction.

The bed plates 5, the chairs 7 and the locking blocks 10 are preferably of cast metal. 70

Each chair 7 has a longitudinal flange member 14 adapted to overlap the outer flange of the rail 9; a brace member 15 adapted to abut against the face of the web of the rail when the rail is in place on the 75 chair; longitudinal channels 16 accommodating the side-members 18 of the bed plate 5, so that the chair will have slight, free, vertical movement relative to the bed plate; a downwardly extended side member 19 80 having a slot 30 adapted to accommodate the tie rod 8 and adapted to permit slight vertical movement of the chair relative to the tie rod; and upright standards 20, supporting the locking block 10. 85

The locking block 10 has a transverse hole (not shown) to receive a bolt 22 extending through the standards 20 and supporting the block; a foot 23 having an inclined lower surface on which the tapered upper surface 90 of the key 13 engages to prevent upward turning of the free end of the block; a hammer lug 24 to receive the blows of a hammer used for driving the block downward; a wedge 25 adapted to engage on one edge of 95 the flange of the rail to press the opposite member of the same flange firmly under the flange member 14 of the chair 7; and a detachable extension 12 at the free end of the block, adapted to bear firmly against the 100 web of the rail to hold it against the brace 15 while the wedge 25 holds the rail flange firmly against the chair flange 14. The extensions 12 are preferably of wrought metal and have inwardly extended members 26 105 adapted to engage in transverse grooves 27 in the blocks 10 to keep the extensions on the blocks. The extensions may be of different thicknesses to compensate for differences in thickness of the web of the rail or differences 110 in width of the flange of the rail.

To install the structure, the concrete road-

bed having a central longitudinal drainage channel as shown, will be built in the usual manner; the drain pipes 3, the tie rods 8 and the bed plates 5 being set in the road-bed during the process of construction; the asphalt cushions 7 will be placed in the boxes of the bed-plates 5; the gage-members 19 of the chairs 7 will be placed on the projecting ends of the tie rods so that the bodies of the 10 chairs will rest on top of the cushions 6; washers 28 will be placed on the tie rods; the nuts 29 on the tie rods will be tightened to hold the parts in place; the rails 9 will be placed in line with each other on the chairs and with the outer flanges of the rails under 15 the flange-members 14, so that the rails will be true to gage; the blocks 10 will be turned and driven downward to cause the wedges 25 to press the rail flanges firmly under the flange-members 14 and to cause the members 20 12 to act on the webs of the rails to press them firmly against the brace-members 15 to tightly hold the rails; and the keys 13 will be driven inward under the feet 23 to 25 securely hold the locking block in its locked position.

Having fully described my invention what I claim as new and desire to secure by Letters Patent is:

- 30 1. The railway structure comprising a permanent road-bed; tie rods embedded in the road bed transverse thereto; box-shape bed-plates embedded in the permanent road-bed; cushions in the boxes of the bed-plates; chairs supported on said cushions and capable of slight vertical movement relative to the respective bed-plates; securing devices on the tie-rods; rails on the chairs; locking blocks hinged on the respective chairs and 35 having members engaging the webs and the edges of the flanges of the rails to lock the rails true to gage on the chairs; and keys holding the locking blocks in locked position.
- 40 2. In a railway structure, the combination of a chair having a flange-member; a

rail having a flange engaging the flange-member of the chair; a locking block hinged on the chair and having an extension engaging the web of the rail and a wedge engaging 50 the flange of the rail; also having a foot with an inclined surface; and a key acting on the inclined surface of the foot to prevent lifting of the locking block.

3. In a railway structure, a chair having 55 a gage-member, a flange-member and standards; in combination with a tie-rod extending through the gage member of the chair; securing devices on the tie-rod preventing movement of the chair in the direction of the length of the tie-rod; a locking block hinged between the standards of the chair and having a foot with an inclined surface; and a key engaging the inclined surface of 60 the foot of the locking-block to prevent 65 turning of the locking-block.

4. In a railway structure, a hinged locking block having an inclined foot, a wedge, an extension and a hammer-lug; in combination with a rail having a web and a flange; 70 means for supporting the locking block in such relation to the rail that blows on the hammer-lug will turn the block downward and drive the wedge against the flange of 75 the rail and the extension against the web of the rail; and a key engaging the foot of the locking block to prevent reverse movement of the locking block.

5. In a structure of the class described, a pivoted locking block having transverse 80 grooves adjacent to the free end of the block; in combination with an extension having members adapted to engage in the transverse grooves of the block.

In witness whereof I have hereunto signed 85 my name at Clinton, Iowa, this 21st day of February, A. D. 1919.

EDWARD FURROW.
